George Wickham Jr.

UNITED STATES PATENT OFFICE.

HORACE WICKHAM, JR., OF CHICAGO, ILLINOIS.

IMPROVED BURGLAR-ALARM.

Specification forming part of Letters Patent No. 55,754, dated June 19, 1866.

To all whom it may concern:

Be it known that I, HORACE WICKHAM, Jr., of Chicago, in the county of Cook and State of Illinois, have invented an Improved Burglar-Alarm; and I do hereby declare that the following is a full, clear, and exact description of the construction and operation of the same, reference being had to the accompanying drawings and letters of reference marked thereon, in which—

Figure 1 is a plan view of my burglar-alarm. Fig. 2 is a longitudinal elevation of the same, with the side of the box removed so as to show the gearing inside.

The object of my invention is to provide a convenient device that can be carried by any person when traveling and applied to a door or window, so as to give an alarm when the door or window is opened from the outside of the room, and thus give warning to the occupant of the approach of danger.

The construction and application of my alarm are different from any heretofore introduced from the fact that it is not necessary that it should be attached permanently or temporarily to the casings of doors or windows, but can be set either on the floor, near the door, or on a window-sill in such a position as to give the required alarm when the window or door is opened.

Another important feature of my invention is that it can be conveniently carried in a common trunk or carpet-sack and applied without disfiguring the casings of doors or windows.

To enable others skilled in the art to make and use my invention, I will describe the method of construction and operation.

A represents the sides, ends, and bottom of the box which incloses the alarm. A'' is the top of the box, which may be hung to the sides by means of hinges and secured by a hook and staple, if desired. A' is the bell, B the hammer-lever, D the gearing, and C the spring, of the common clock-alarm.

E shows the plates which support the gearing of the alarm, constructed in the usual manner. These plates may be secured to the inside of the box by means of screws or otherwise, as most convenient, only so that the alarm is held securely in the box.

F represents the standard passing through the bottom of the box A, used for discharging the clock-alarm.

t shows an elliptical opening made in the upper part of the standard F in order that the point s of the support u may pass into it and steady the standard when operating the alarm.

G shows the cap attached to the standard F, which is used to lock against the arm H and keep the clock-alarm from operating when desired.

I represents the common thumb-screw used both in holding the plate G against the arm H and discharging the alarm.

Operation: k shows the post on which the key is put when winding up the alarm. In order that the alarm may be given only when required, the screw I must be turned against the box, so as to prevent the plate G from passing above the arm H, in which position the box can be carried without giving an alarm. In setting the alarm the screw I must be turned down, as shown by the dotted lines J, and the box must be set so that when the door or window is opened they will strike against the screw I J, as shown at Fig. 2, and the alarm will be given.

Having thus fully described my device, what I claim, and desire to secure by Letters Patent of the United States, is—

The operating of the clock-alarm by means of the arm H, support U, standard F, and screw I, when constructed substantially as set forth and operated as described.

HORACE WICKHAM, JR.
